UNITED STATES PATENT OFFICE

2,082,394

RAIL JOINT CLOSER

Nels Hamre, Miles City, Mont.

Application June 25, 1936, Serial No. 87,299

2 Claims. (Cl. 254—43)

The present invention relates to rail joint closers and the object of the invention is to provide means to be applied to rail joints for adapting the positions of railroad rails with respect to each other, to close or open the joints and comprehend a pair of members engageable with the rails with controlling means therefor.

Another object of the invention resides in the provision of means of this nature which is simple in its construction, inexpensive to manufacture, easy to manipulate, thoroughly efficient and reliable in use and operation, and otherwise well adapted to the purpose for which it is designed.

With the above and numerous other objects in view as will appear as the description proceeds, the invention consists in certain novel features of construction, and in the combination and arrangement of parts as will be hereinafter more fully described and claimed.

In the drawings:—

Figure 1 is a top plan view of a pair of adjoining rails, showing the rail joint closure applied in horizontal position across the balls of the rail.

Figure 2 is a side elevation of the construction shown in Figure 1.

Figure 3 is a detail sectional view taken substantially on the line 3—3 of Figure 2.

Figure 4 is a sectional view taken substantially on the line 4—4 of Figure 1.

Figure 5 is a perspective view of one of the members.

Figure 6 is a perspective view of one of the jaws.

Referring to the drawings in detail it will be seen that numeral 5 denotes the base of a pair of end to end disposed rails. Letters A denote a pair of members comprising bodies 6 and arms 6' obliquely disposed in respect to each other. The bodies 6 are provided with notches or recesses 8.

The notches 8 are provided at opposite ends with ball 5 rail engaging portions 9 having co-operable therewith jaws 10 with ratchet-like teeth 11, while the other end is provided with a pointed portion 12. The arms 6' are provided with openings 14. A bolt 15 extends through said opening having a head and washer 16 at one end and a nut threadedly mounted as at 18 at the other end. Obviously by tightening the thread on the bolt the rails may be brought together with the jaws 10 and their teeth 11 engaging with the balls of the rails.

It is thought that the construction, operation, utility, and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

What is claimed is:—

1. Means for tightening the ends of rails comprising a pair of members, the members comprising bodies and arms, the arms being obliquely disposed with respect to the bodies, the bodies having notches provided with a pointed portion at one end and a fulcrum portion at the other end for engagement with the rails and the arms having openings, a bolt extendible through the openings for drawing the arms toward each other, and jaws with ratchet teeth engageable with the ball of the rails and secured in the bodies at the fulcrum portion of the notches, the jaws being provided with grooves seating the fulcrum portions of the said bodies.

2. Means for tightening the ends of rails comprising a pair of members, the members comprising bodies and arms adapted to be applied in horizontal position across the balls of the rails with the bodies obliquely disposed with respect to the balls of the rails, the said bodies having notches for engagement with the rails and the said arms having openings, each body having an inwardly directed projection at one end of the notch and adjacent one side of the body and also having a pointed portion at the opposite end of the notch and diagonally opposed to the said projection, a bolt extendible through the openings for drawing the members toward each other to cause each of the said bodies to move on its pointed portion as a fulcrum and in a direction binding the said pointed portion against the rail, and jaws with ratchet teeth positioned in the said notches to come between the ball of the rails and the projections of the bodies.

NELS HAMRE.
